UNITED STATES PATENT OFFICE

FRED E. ASELTINE, OF DAYTON, OHIO, ASSIGNOR TO DELCO PRODUCTS CORPORATION,
OF DAYTON, OHIO, A CORPORATION OF DELAWARE

CHARGE FORMING DEVICE

Application filed November 2, 1929. Serial No. 404,323.

This invention relates to charge forming devices for internal combustion engines and most particularly to that type of charge forming devices which comprises a plurality 5 of primary carburetors each of which is adapted to deliver a primary mixture of fuel and air to one of a plurality of secondary carburetors located adjacent the engine intake ports and in which additional air is 10 mixed with the primary mixture before the latter enters the engine cylinders under certain operating conditions.

An example of a charge forming device of this type is disclosed in the application of 15 Fred E. Aseltine, Wilford H. Teeter, Carl H. Kindl and F. D. Funston, Serial Number 370,179, filed May 13, 1929.

It is the general object of the present invention to provide means for securing improved operation of the engine during the acceleration period accompanying an opening movement of the throttle and more particularly when the opening of the throttle occurs substantially immediately after the throttle 25 has been moved to substantially closed position.

This general object is accomplished according to the present invention by the provision of means for supplying additional fuel to the 30 primary mixture passages during the closing movement of the throttle. This fuel is drawn into the mixture passages as the throttle is closed and since the velocity of flow through said passages is very slow when the 35 throttle is substantially closed it will require an appreciable time for such fuel to be drawn out of the mixture passages, and most of it will remain in said passages between the point where it is admitted thereto and the 40 outlet ends thereof until the throttle is again opened so that it is then immediately available and is carried into the engine intake ports practically simultaneously with the 45 opening of the throttle.

Further objects and advantages of the 50 present invention will be apparent from the following description, reference being had to the accompanying drawings wherein a preferred embodiment of one form of the present invention is clearly shown.

In the drawings:

Fig. 1 is a vertical longitudinal section through a charge forming device embodying the present invention.

Fig. 2 is a side elevation of the carburetor unit forming part of the charge forming device, partly broken away to show certain parts in section and having a cover plate removed to show the valve operating mechanism.

Fig. 3 is a rear elevation of the carburetor unit partly in section.

Figs. 4 and 5 are horizontal sections on the lines 4-4 and 5-5 of Fig. 1.

The device comprises a main air manifold 65 10 having three outlet branches, the middle branch 12, being shown herein. Each of these branches communicates with one of the ports of a multicylinder engine and each is provided with an attaching flange 14 which is 70 adapted to be secured to the engine block in the usual way, while adjacent the inlet of the manifold is a flange 16 to which the main carburetor unit, hereinafter described, is 75 adapted to be secured, as shown in Fig. 1.

The main carburetor unit comprises a main housing 18 in the form of a single casting having a flange 20 adapted to be secured to the flange 16 by screws 22. A valve controlled air inlet coupling 24 is secured in 80 position in an opening in the top of the housing 18 by screws 26, or in any other suitable manner. A casting 28, having certain fuel passages formed therein, is secured by screws 30 to the bottom of the main housing and a 85 sheet metal fuel bowl 32 is held tight against an annular shoulder 34 on the bottom of the main housing by a screw 36 screwed into the casting 28, suitable gaskets being provided wherever necessary to prevent leakage of the 90 fuel. A fuel conduit, which is not shown herein, supplies fuel to the fuel bowl and a float 38 operates to maintain a substantially constant level of fuel in the bowl in the usual manner.

A plurality of angular primary mixture passages, indicated in their entirety by the reference character 40 and hereinafter more fully described, are provided in the lower part of the main housing. Communicating 95 100

with the vertical portion of these mixture passages through orifices 42 are three chambers 44 which, for convenience, are designated fuel supply chambers. Fuel is admitted directly to these chambers by nozzles 46 and is mixed therein with a small quantity of air admitted thereto by a slot 48, formed in a partition separating the fuel supply chambers from a main air chamber to be more fully described later. This mixture of fuel and air flows from the fuel supply chambers through the orifices 42 to the primary mixture passages.

Fuel is supplied to the nozzles 46 through a vertical fuel passage 50 formed in the casting 28 and communicating at its upper end with a horizontal channel 52 which communicates directly with all of the nozzles 46, while at its lower end the passage 50 connects with a horizontal passage 54 which, in turn, communicates with the interior of the float bowl 32 and is provided with a calibrated metering plug 56 having a fixed orifice therein, as shown in Figs. 3 and 5. Each of the fuel nozzles 46 is provided with a restricted metering orifice 58 as illustrated in Fig. 1.

Each nozzle is provided with a main fuel outlet 60 in its top and a secondary fuel outlet comprising two orifices 62 and 64 formed in the vertical wall of the nozzle adjacent the bottom of the fuel supply chamber. At relatively high speeds the suction within the fuel supply chambers is sufficient to effect a flow of fuel from the main orifice 60 in the top of each of the nozzles, but during idling, or low speed operation under load, the suction communicated to the nozzles is sufficient to lift the fuel only to some point intermediate the main fuel inlet 60 and the secondary fuel feeding orifices 62 and 64, at which time the fuel will flow from the latter by the action of gravity.

The primary mixture passages are controlled by a single throttle valve 66 which extends across all of the passages, is provided with grooves 68 which register with said passages, and is operated by means more fully described later. The primary mixture passages register with conduits for conveying the primary mixture to the secondary mixing chambers, when the device is assembled. These conduits comprise tubes cast in position in the manifold during the casting of the latter as fully shown and described in the above copending application. Only the tube 69 for conveying primary mixture to the secondary mixing chamber formed in the middle branch of the manifold is shown herein, since these tubes, of themselves, form no part of the present invention and their specific construction is entirely immaterial thereto.

All of the fuel supply chambers 44 communicate with a chamber 70 which may be termed a primary air chamber. The cham-

ber 70 and all of the chambers 44 are separated by the partition plate 72, hereinbefore referred to, from a main air chamber 74, and the fuel supply chambers are separated from the vertical portions of the primary mixture passages by a vertical partition 76, which is formed as an integral part of the main housing and on which the partition 72 is supported. The fuel supply chambers 44 are separated from each other by vertical partitions 78 which are also integral with the main housing.

All of the air supplied to the carburetor is admitted through the air inlet coupling 24 and is controlled by a valve 80 normally held against its seat 82 by a spring 84 received between the valve and a flange 86 projecting from a sleeve 88 slidably mounted on a fixed sleeve 90 which guides the stem 92 to which the air valve is secured. Under normal operating conditions the sleeve 88 occupies the position shown in Fig. 1, but may be lifted by the choke lever 94 until it engages the valve 80 to hold said valve closed for the purpose of aiding in starting the engine. The choke mechanism forms no part of the present invention and will not be more fully described herein, but is completely described in the above mentioned earlier application.

The valve 80 admits air directly to the main air chamber 74, which supplies air to the primary air chamber as above set forth, and also to the secondary mixing chambers in the manifold by means of a secondary air passage 96, controlled by a manually operable valve 98, secured to a shaft 100 rotatably mounted in the main housing, and a suction operated valve 102, secured to a shaft 104 which is also rotatably mounted in the housing 18. The operating mechanism for these valves will be described hereinafter. In addition to the air supplied to the chamber 70 and that supplied to the secondary mixing chambers as above disclosed, the main air chamber also communicates directly with the vertical portions of the primary mixture passage and supplies air thereto.

The slot 48 admitting air to the fuel supply chambers is considerably larger than the total area of the three orifices 42 which connect the fuel chambers with the primary mixture passages. Because of this difference in area of the air inlet and outlet to the fuel supply chambers, it is obvious that the flow of air through these chambers must necessarily be at low velocity under all operating conditions and at all engine speeds. For this reason there is substantially no velocity head created at the fuel nozzles under any operating conditions, the reason being more fully set forth in the earlier applications above referred to, and the suction which is effective to cause a flow of fuel from the nozzles is substantially the static suction

of the air chamber 74 as determined by the main air valve spring.

During operation at all engine speeds below a certain predetermined speed, for example, that corresponding to a vehicular speed of 20-25 miles per hour on the level, the mixture conveyed through the primary mixture conduits is sufficient to provide the proper quantity of fuel charge and is conveyed to the engine without mixture with additional air in the secondary mixing chambers. At higher engine speeds than this, however, the valves controlling the secondary air passage are opened to increase the quantity of mixture supplied to the engine.

The manually operable valve 98 is operated by the primary throttle after the primary throttle has made a certain amount of independent movement and the valve 102 is opened by the engine suction substantially simultaneously with the opening of the valve 98. To operate these valves an operating plate 106 is secured to one end of the throttle, in the manner disclosed in the above application, and is pivotally connected by a link 108 to an arm 110 which is secured to the shaft 100 of the valve 98. The parts are normally held in the position shown in Fig. 2 with the valves 98 closed and during the first part of the opening movement of the throttle the point of connection of the link 108 with the plate 106 moves substantially in the arc of a circle, the center of which is the point of connection between the link 108 and the arm 110, so that the arm 110 remains stationary. After this amount of movement of the primary throttle further movement thereof will move the arm 110 and open the valve 98. Because of a slight tendency of the parts to bind, the link 108 is connected to the arm 110 by means of a pin 112 projecting from said arm and extending through a short slot (not shown) in the link. The pin is normally held in one end of the slot by means of a spring 114 as fully described in the earlier application.

Whenever the valve 98 is opened, the engine suction opens the valve 102 and the opening movement of this valve is retarded by a dashpot comprising a cylinder and cooperating piston (not shown herein) but which is connected by a link 116 to an arm 115 secured to one end of the shaft 104. On closing movements of the valve 98 the suction operated valve 102 is closed by an arm 118 pivotally mounted on the operating plate 106. This arm engages a pin 120 projecting from link 116 and the arm is moved to effect return of the suction operated valve to normal position by the spring 122, one end of which is connected to an ear 124 projecting from the arm 118 while the other end is secured to the main housing as shown in Fig. 2. This valve operating mechanism constitutes no part of the present invention, and for a more detailed

description thereof reference may be had to the application herein referred to in which the valve operating mechanism is the same as disclosed herein.

On opening movement of the throttle, suction in the main air chamber is increased and the main air valve 80 is opened to permit an increased flow of air past the valve. It has been found necessary to retard the opening movement of this valve to prevent fluttering of the valve and to prevent the admission of sufficient air to temporarily lean the mixture in the primary mixture passages before the valve comes to rest. A dashpot comprising the cylinder 130 formed in the casting 28 and a piston 132 secured to the lower end of the valve stem 92 is provided for this purpose. The dashpot shown is adapted to be filled with fuel by leakage around the piston and the dashpot may be of any conventional form so far as the present invention is concerned.

On opening of the throttle it has also been found necessary to provide temporarily, a somewhat enriched mixture in order to properly operate the engine during the acceleration period for reasons which are well known to those skilled in this art. For this purpose a fuel pump has been provided which is operated by the primary throttle and comprises a cylinder 134 formed in the casting 28 and closed at its lower end by a plate 136 secured by screws 138 to the bottom of said casting. A pump piston 140 is received within the cylinder and is pivotally connected to an operating link or rod 142, pivotally connected by pin 144 to the operating plate 106, which is secured as hereinbefore described to the primary throttle. On opening movements of the throttle the member 106 is moved in a clockwise direction and the piston 140 is depressed, while on closing movements of the throttle the piston is returned to the position shown in Fig. 2 by a spring 146, received in the cylinder 134 between the piston and the plate 138.

The fuel delivery passage from the pump comprises a horizontal passage 148 communicating with a vertical passage 150 leading to a fuel well 152 formed in the upper part of the casting 28. A plurality of horizontal passages 154 connect the bottom of this well with an overflow chamber 156 which is connected at its upper end by an orifice 158 with an auxiliary fuel reservoir 160, the function of which is more fully described later. The middle passage 154 communicates directly with the middle one of three vertical passages 162, formed in the casting 28. The middle passage 162 registers with a corresponding passage in the wall of the housing 18, which is adapted to supply fuel to the middle mixture passages 40. The outer passage 154 communicates with the outer passages 162, which connect with horizontal

channels 164, formed in the top of the casting 28 and communicating at their outer ends with vertical passages in the wall of the housing, which lead to the two outer primary mixture passages 40. Restrictions 166 are provided in the outlet ends of the fuel delivery passages adjacent their point of communication with the mixture passages. It will be obvious that on downward movement of the pump piston which accompanies any opening movement of the throttle, fuel will be forced into the well 152 and through the overflow chamber into the auxiliary fuel chamber 160 while a part of the fuel delivered to the well 152 will pass through the various delivery passages into the primary mixture passages to enrich the mixture temporarily during the acceleration period.

A passage 168 as shown in Fig. 4 admits air to the top of the fuel reservoir 160 and serves the double purpose of venting said reservoir and supplying air to the fuel which passes into the primary mixture passages so that an emulsion of fuel and air is delivered thereto. By admitting air in this manner, the suction communicated to the fuel delivery passage is never sufficient to draw fuel from the pump cylinder and no fuel is supplied to the mixture passages by passages 162 except on the downward stroke of the pump piston.

The auxiliary reservoir 160 is adapted to supply fuel to the primary mixture passages during closing movements of the throttle and for this purpose a delivery passage 170 is provided, which communicates with the reservoir at the bottom and with a bore 172 formed in the casting 28. A plug 174 is screwed into this bore and is provided with a central passage 176 which is normally closed by a valve 178 held in its closed position by a spring 180 above the valve as shown in Fig. 1. The plug 174 is also provided with lateral orifices 182 which communicate with the central passage 176 and with an angular passage 184 which conducts fuel from the auxiliary reservoir 160 back into the well 152 whenever the valve 178 is opened, whereby such fuel may be drawn into the primary mixture passages through the passages 162. The valve 178 is opened by an arm 186 carried by the piston rod 142 on the return of the piston to normal position when the throttle is moved toward closed position, the arm being adapted to engage the valve when the throttle is nearly closed. The arm 186 is secured by rivets or in any other desirable manner to the piston rod 142 and is of such shape that its free end is immediately under the stem of the valve 178.

The function and purpose of this device is substantially as follows: It has been found by experiment that where a pump such as that above described is used, there are certain operating conditions under which the pump does not supply fuel to the intake ports suf-

ficiently rapidly to satisfactorily operate the engine, and for a very brief period the engine may actually miss firing. An example of such operating conditions is on opening of the throttle to accelerate the speed following substantially immediately the closing of the throttle. For instance, if the driver of the vehicle on which the device is used removes his foot from the accelerator pedal and applies the brake, the primary throttle is closed automatically and the vehicle slowed down. The fuel mixture in the primary passages between the throttle and the engine is swept out of the mixture conduits and into the intake ports under these conditions so that only a very small quantity of fuel remains in the conduits between the throttle and the engine by the time the throttle can be again opened. Then if the throttle be opened to increase the vehicular speed there would be a brief interval during which the engine will not receive sufficient fuel to operate properly. It is the purpose of the present invention to supply additional fuel to the mixture passages through the passages 162 as the throttle is closed. This additional fuel is drawn into the passages between the throttle and the engine ports as the engine is slowing down and before the throttle is again opened, and since the rate of flow through the conduits is relatively slow when the throttle is closed most of this fuel will remain in the conduits until the throttle is again opened. Then when the throttle is opened, this additional fuel is carried into the ports and by the time such fuel has been drawn out of the passages, the additional fuel supplied by action of the pump piston will reach said mixture passages so that there will not be an interval in which the mixture is too lean.

The secondary mixing chambers may consist of any form of device for straightening and accelerating the flow of air past the ends of the primary mixture conduits and may be of the type shown in the earlier applications above referred to.

It will be noted that for convenience this invention has been incorporated in a device having the same general construction as disclosed in application Serial Number 370,179 but the present invention is in no way particularly related to that specific device and may be incorporated in many other devices of this general character.

While the form of embodiment of the present invention as herein disclosed, constitutes a preferred form, it is to be understood that other forms might be adopted, all coming within the scope of the claims which follow.

What is claimed is as follows:

1. A charge forming device for internal combustion engines comprising a mixture passage, means for supplying fuel and air

thereto, a throttle, and means for supplying additional fuel to the mixture passage on closing movement of the throttle.

2. A charge forming device for internal combustion engines comprising a mixture passage, means for supplying fuel and air thereto, a throttle, and means operated by the throttle for supplying additional fuel to the mixture passage on closing movements 10 of the throttle.

3. A charge forming device for internal combustion engines comprising a mixture passage, an air inlet therefor, a main fuel inlet therefor, a secondary fuel inlet for said mixture passage, a throttle, and means for causing a flow of fuel from said secondary fuel inlet on closing movement of the throttle.

4. A charge forming device for internal combustion engines comprising a mixture passage, an air inlet therefor, a main fuel inlet therefor, a normally ineffective secondary fuel inlet, a throttle, and means for rendering said secondary fuel inlet effective 25 to supply fuel to the mixture passage on closing movement of the throttle.

5. A charge forming device for internal combustion engines comprising a mixture passage, an air inlet therefor, a main fuel inlet therefor, a secondary fuel inlet for said mixture passage, ineffective under all operating conditions without movement of the throttle and means for rendering said inlet effective to supply fuel to the mixture passage on closing movements of the throttle.

6. A charge forming device for internal combustion engines comprising a mixture passage, an air inlet therefor, a main fuel inlet therefor, a secondary fuel inlet therefor, a throttle, and means operated by the throttle for causing a flow of fuel through said secondary fuel inlet on closing movements of said throttle.

7. A charge forming device for internal combustion engines comprising a mixture passage, an air inlet therefor, a main fuel inlet therefor, a secondary fuel inlet therefor ineffective under all operating conditions without movement of the throttle, and means operated by the throttle for rendering said secondary fuel inlet effective to supply fuel to the mixture passage on opening or closing movements of the throttle.

8. A charge forming device for internal combustion engines comprising a mixture passage, fuel and air inlets therefor, a throttle, a pump operated by the throttle for supplying additional fuel to the mixture passage on opening movements of the throttle and means operated by the pump for supplying additional fuel to the mixture passage on closing movements of the throttle.

9. A charge forming device for internal combustion engines comprising a mixture passage, fuel and air inlets therefor, a throt-

tle, a pump operable on opening movements of the throttle to supply additional fuel to the mixture passage during the acceleration period and means operated by the pump on closing movements of the throttle to supply 70 additional fuel to the mixture passage on deceleration.

10. A charge forming device for internal combustion engines comprising a mixture passage, fuel and air inlets therefor, a throttle, a fuel reservoir for supplying additional fuel to the mixture passage and adapted to be filled with fuel on opening movements of the throttle, and means operable on closing movements of the throttle for rendering said 80 reservoir effective to supply fuel to the mixture passage.

11. A charge forming device for internal combustion engines comprising a mixture passage, fuel and air inlets therefor, a throttle, a fuel reservoir for supplying additional fuel to the mixture passage and adapted to be filled with fuel on opening movements of the throttle, a valve normally preventing a flow of fuel from the reservoir to the mixture passage and means operable on closing movements of the throttle for operating said valve.

12. A charge forming device for internal combustion engines comprising a mixture 95 passage, fuel and air inlets therefor, a throttle, a fuel reservoir, a pump operated on opening movements of the throttle and adapted to fill said reservoir with fuel, and means operated by said pump on closing movements of the throttle for rendering said reservoir effective to supply fuel to the mixture passage.

13. A charge forming device for internal combustion engines comprising a mixture 105 passage, fuel and air inlets therefor, a throttle, a fuel reservoir adapted to supply additional fuel to the mixture passage, a valve controlling the flow of fuel from said reservoir, a pump piston operable to simultaneously supply additional fuel to the mixture passage and to fill said reservoir with fuel on its pumping stroke, and means carried by said pump piston and adapted to operate said valve when the piston is returned to normal position.

14. A charge forming device for internal combustion engines comprising a mixture passage, fuel and air inlets therefor, an accelerator well adapted to supply fuel to the mixture passage on opening movement of the throttle, an auxiliary fuel reservoir for supplying additional fuel to the mixture passage, said reservoir communicating with the accelerator well and adapted to receive fuel therefrom when said well is supplied with fuel, means for supplying fuel to said well on opening movement of the throttle and means for rendering said reservoir effective 130

to supply fuel to the mixture passage on closing movement of the throttle.

15. A charge forming device for internal combustion engines comprising a mixture passage, fuel and air inlets therefor, an accelerator well adapted to supply fuel to the mixture passage on opening movement of the throttle, an auxiliary fuel reservoir for supplying additional fuel to the mixture passage, said reservoir communicating with the accelerator well and adapted to receive fuel therefrom when said well is supplied with fuel, a fuel pump for supplying fuel to the well on opening movement of the throttle 10 and means operated by said pump for rendering said reservoir effective to supply fuel to the mixture passage on closing movement of the throttle.

16. A charge forming device for internal combustion engines comprising a mixture passage, fuel and air inlets therefor, an accelerator well adapted to supply fuel to the mixture passage on opening movement of the throttle, an auxiliary fuel reservoir for supplying additional fuel to the mixture passage, said reservoir communicating with the accelerator well and adapted to receive fuel therefrom when said well is supplied with fuel, a fuel pump operated by the throttle 25 for supplying fuel to the well on opening movement of the throttle, and means for causing a flow of fuel from said reservoir through said passage to the accelerator well on closing movements of the throttle.

35. 17. A charge forming device for internal combustion engines comprising a mixture passage, fuel and air inlets therefor, an accelerator well adapted to supply fuel to the mixture passage on opening movement of the 40 throttle, an auxiliary fuel reservoir for supplying additional fuel to the mixture passage, said reservoir communicating with the accelerator well and adapted to receive fuel therefrom when said well is supplied with fuel, a fuel passage connecting the accelerator well and auxiliary reservoir, a valve controlling the flow through said passage, means for supplying fuel to said well on opening movements of the throttle, and means for operating said valve on closing movements of 45 said throttle.

18. A charge forming device for internal combustion engines comprising a primary mixture passage, a secondary mixing chamber 55 into which said primary mixture passage delivers a primary mixture of fuel and air, fuel and air inlets therefor, a primary throttle controlling the flow through said primary mixture passage, means operated by the primary throttle for supplying additional fuel to the primary mixture passage on opening movements of said throttle, and means operated on closing movements of the throttle to supply additional fuel to the primary mixture passage during deceleration.

19. A charge forming device for a multi-cylinder internal combustion engine comprising a plurality of secondary mixing chambers, a plurality of primary mixture passages delivering a primary mixture of fuel and air to said secondary mixing chambers, means for supplying fuel and air to said primary mixture passages, a fuel pump operative on opening movements of the throttle to supply additional fuel to all of 70 said mixture passages, and another means operative on closing movement of the throttle to supply additional fuel to said mixture passages.

20. A charge forming device for internal combustion engines comprising a mixture passage, fuel and air, inlets therefor, a throttle, a fuel reservoir adapted to supply additional fuel to the mixture passage, a pump operated on opening movements of the 80 throttle, a valve controlling the flow of fuel from the reservoir to the mixture passage, and means operated by said pump on closing movements of the throttle for opening said valve.

21. A charge forming device for internal combustion engines comprising a mixing passage, fuel and air inlets therefor, a throttle, a fuel reservoir, a pump piston operable to simultaneously supply additional 95 fuel to the mixture passage and to fill said reservoir with fuel on its pumping stroke and operable on its return to normal position to render said reservoir effective to supply fuel to the mixture passage.

In testimony whereof I hereto affix my signature.
